UNITED STATES PATENT OFFICE.

DAVIDE BONZI, OF EAST LYME, CONNECTICUT.

REFRIGERATOR.

1,373,294.

Specification of Letters Patent. Patented Mar. 29, 1921.

Application filed October 6, 1920. Serial No. 415,011.

To all whom it may concern:

Be it known that I, DAVIDE BONZI, a subject of the King of Italy, residing at East Lyme, in the county of New London and State of Connecticut, have invented certain new and useful Improvements in Refrigerators, of which the following is a specification.

This invention relates to certain new and useful improvements in refrigerators and has for one of its objects to provide a refrigerator of the top icer type wherein a hinged lid is carried by the top of the refrigerator frame to provide for placing the ice within the refrigerator.

A further object of the invention has particular reference to the body construction of the refrigerator, the same being formed of cementitious material with food and ice compartments communicating with each other by air passages with the body of the refrigerator supported on the ball bearing casters to facilitate moving of the same from one place to another.

A further object of the invention has particular reference to a drain spout associated with the ice chamber, a screen covered perforated pipe being located in the bottom of the ice compartment or chamber and communicating with a faucet upon the outer wall of the refrigerator for purposes of draining the ice compartment of water.

With the above and other objects in view, the present invention consists in the novel form, combination and arrangement of parts hereinafter more fully described and shown in the accompanying drawings, in which like reference characters indicate similar parts throughout the several views.

In the drawings, Figure 1 is a front elevational view of a refrigerator constructed in accordance with the present invention.

Fig. 2 is a top plan view of the same,

Fig. 3 is an end elevational view,

Fig. 4 is a vertical sectional view taken on line IV—IV of Fig. 1 showing the cold air passages from the ice compartment to the food chambers,

Fig. 5 is a horizontal sectional view taken on line V—V of Fig. 1 showing the drain

pipe for the ice compartments and the air passages between the ice and food compartments,

Fig. 6 is a vertical sectional view taken on line VI—VI of Fig. 3 showing the concrete construction of the refrigerator, the ice and food compartments, and the wall brackets for the food compartment trays,

Fig. 7 is a perspective view of the longitudinal metallic side brace bar for the lower end of the refrigerator,

Fig. 8 is a perspective view of the transverse base supporting metallic bar of the refrigerator, and

Fig. 9 is a fragmentary sectional view of the lower end of the refrigerator showing a caster mounting for one of the supporting rollers.

Briefly described, the present invention has for its primary object to provide a refrigerator of cementitious or concrete construction having a central ice compartment and lateral food compartments. Access is gained to the ice compartment by a hinged top door thereby providing a refrigerator of the top icer type. A drain pipe is partly embedded in the bottom wall of the ice compartment, being covered by a screen and perforated and is in communication with a faucet arranged exteriorly of the refrigerator for draining the ice compartment of water. Side doors permit access to the food compartments while a novel construction of brace bars extend longitudinally and transversely of the lower edges of the refrigerator body to support the same. A ball bearing revolving caster is mounted at each lower corner of the refrigerator to facilitate an easy moving of the same from one position to another.

Referring more in detail to the accompanying drawings, there is illustrated a refrigerator of concrete construction, being preferably rectangular in plan view and embodying a front wall 1, top wall 2, end walls 3, rear wall 4, and a bottom wall 5. Vertical partitions 6 extending transversely of the interior of the refrigerator divide the same into three compartments, a central ice compartment 7 and lateral food compartments 8. Access is gained to the ice com-

partment 7 for filling the same by door 9 of concrete construction braced by a metallic supporting frame 10, the same being hinged to the top wall 2 as at 11 and it being provided upon the free swinging end thereof with a handle 12. The lid or cover 9 is set within the ice compartment 7 with the upper face thereof lying flush with the upper face of the top wall 2.

10 As shown in Figs. 4, 5, and 6, a drainage pipe and faucet outlet therefor is associated with the ice compartment 7, the pipe 13 being embedded in the bottom wall 7' of the ice chamber, extending through the rear wall thereof for the reception of a cap 14 while the forward projecting end extending through the front wall 1 is provided with a faucet outlet 15. The pipe is provided with a plurality of perforations 16 as shown in Figs. 5 and 6 through which water from the compartment 7 flows to the drain pipe 13.

15 The cold air circulation between the ice compartment 7 and the food compartments 8 passes through the inclined openings 17 in the partition walls 6 as shown in Figs. 4 and 6, the openings being arranged approximately midway and adjacent the upper end of the ice compartment.

20 Each food compartment 8 is of like construction, the inner faces of the end walls 3 and the adjacent faces of the partition walls 6 being formed with horizontally aligned ledges 18 for the sliding reception of food supporting trays. A door 19 is provided in the front wall 1 of the refrigerator body for each food compartment 8 and is hinged thereto as at 20 while a lock device 21 secures the free swinging edge thereof in closed position.

25 A novel form of metallic brace is associated with the lower end of the refrigerator body, a brace bar being provided for the front and rear edges thereof extending longitudinally while end brace plates extend transversely of the body. These bracing plates are shown in detail in Figs. 7 and 8, the longitudinal brace plate embodying a central body portion 22 having inclined downward extensions 23 continuing in straight end extensions 24 while corresponding side edges of the end extensions 24 carry angle plates 25. The longitudinal brace plates 22 underlie each lower side edge of the refrigerator body and are secured thereto by fastening devices passing through the openings 24' in the end extensions while the angle plates 25 of said extensions extend upwardly for engagement with the outer face of the adjacent side wall of the refrigerator. The end transverse bracing plates are similarly formed, each including a central body portion 26, downward inclined members 27 and end extensions 28 with angle plates 29 carried by corresponding side edges thereof. In a like manner, the end trans-

verse bracing plates are secured to the lower edges of the refrigerator body by fastening devices passing through the openings 28' in the end extensions.

20 A revolving ball bearing caster is associated with each corner of the refrigerator, the same embodying a disk 30 carrying a depending fork projection 31 for supporting a floor roller 32 while a bearing plate 33 is secured by rivets 34 to the end extensions 24 and 28 of the longitudinal and transverse bracing plates. Ball bearings 35 are interposed between the disk 30 and plate 33 and the disk 30 is rotatably mounted beneath the plate 33 by the vertical bearing pin 36.

25 As clearly shown in Fig. 6, the bottom wall 7' of the ice compartment 7 and the bottom walls 8' of the food compartments are of increased cross sectional area thereby providing a substantial mounting base combined with the metallic bracing plates for the lower end of the refrigerator body.

30 While there is herein shown and described what is believed to be the preferred embodiment of the invention, it is nevertheless to be understood that minor changes may be made therein without departing from the spirit and scope of the invention as claimed.

35 What is claimed as new is:

1. A refrigerator of the type described comprising a concrete body of integral construction, embodying vertical spaced partitions dividing the same into a central ice compartment and lateral food compartments, a top cover for the ice compartment, side doors for the food compartments, a drainage pipe extending transversely of the bottom wall of the ice compartment and metallic bracing plates for the lower end of the refrigerator.

40 105 2. A refrigerator of the type described comprising a concrete body of integral construction, spaced partitions therein dividing the same into a central ice compartment and lateral food compartments, said partitions having air passages forming communication between the ice compartment and the food compartments, a top cover for the ice compartment, side doors for the food compartments, a drainage pipe extending transversely of the bottom wall of the ice compartment, a faucet arranged exteriorly of the refrigerator body and communicating with the drainage pipe, and metallic bracing plates disposed at the side edges and ends of the bottom of the refrigerator body.

45 110 115 120 125 3. A refrigerator of the type described comprising a concrete body of integral construction, spaced partitions therein dividing the same into a central ice compartment and lateral food compartments, said partitions having air passages forming communication between the ice compartment and the food compartments, a top cover for the ice compartment, side doors for the food com-

parts, a drainage pipe extending transversely of the bottom wall of the ice compartment, the bottom walls of the ice and food compartments being of increased cross
5 sectional area with the lower faces of the bottom walls of the food compartments extending below the bottom wall of the ice

compartments and side and end bottom bracing plates formed complementally to the contour of the bottom face of the refrigerator body and secured thereto at the ends thereof.

In testimony whereof I affix my signature.
DAVIDE BONZI.
